Attorney

UNITED STATES PATENT OFFICE

WILLIAM KAMPAS, OF DES MOINES, IOWA

SHADE ROLLER

Application filed April 4, 1930. Serial No. 441,621.

This invention relates to a new and improved window shade roller of a longitudinally extensible all metal spring wound type.

In carrying the invention into practice, I have involved and produced a roller construction which is characterized by novel details arranged in a practical manner to fulfill the requirements of a device of this class in a satisfactory manner, the structure being regarded as a distinct contribution to the art and susceptible of fulfilling the requirements of a device of this class in a more satisfactory manner.

The specific details and their relative arrangement and association will become more readily apparent from the following description and drawings.

In the drawings:

Figure 1 is a view in section and elevation of the complete structure as developed in accordance with the present invention.

Figure 2 is an enlarged transverse cross section on the line 2-2 of Figure 1.

Figure 3 is an end view of the structure observing it in a direction from right to left in Figure 1.

Figure 4 is a fragmentary perspective view of a special shade clamp.

Figure 5 is a fragmentary perspective view of a portion of the retainer strip.

Figure 6 is a sectional view of the especially constructed flanged cap.

The roller 7 is made up of two companion parts, namely a male tube 8 fitting telescopically into a female tube, on the left hand end of the tube 8 there being a centralized pintle 10 fitting into a bearing hole in the complementary bracket 11. On the end of the female tube 9 is a concavo-convex cap 12 having a centralized shank 13 removably fitting into the notch in the other wall bracket 14 as seen in Figure 3. This cap has a flange 15.

Pivotaly mounted on the bracket 14 is a retaining pawl 16 whose bent free end extends over and embraces the flange 15. This pawl is held down in frictional engagement with the flange and cap through the medium of a coiled retention spring 17, one end being anchored on the pawl, and the other end fas-

tened to the bracket 14 as seen clearly in Figure 3.

The letter A designates the internal coiled tensioning and return spring. This is of any suitable construction. Both of the tubular sections of the roller are formed with interfitting, inwardly pressed channel-shaped keepers 18 as seen in Figure 2. This extensible keeper arrangement serves to accommodate the especially designed clamping device 19 for the shade 20. The clamp comprises a hooked retaining flange 21 which is pressed against the free end of the shade in the manner represented in Figure 2. In addition there is a guard and fastening lip 22 which takes the position also represented in Figure 2. The numeral 23 designates a finger piece.

The numeral 24 represents a longitudinally bowed compressing strip which is interposed between the keeper 18 and the back of the clamping device 19 as also seen in Figure 2. This serves to press the clamp outwardly against the converging walls of the channel-shaped keeper 18 to hold the clamp frictionally in adjusted position.

The features to be noted in connection with this new arrangement are these. First, I call attention to the longitudinally extensible and adjustable construction of the roller 7 made up of the telescopically connected tubes 8 and 9 having the interfitting channel-shaped portions 18 defining an adjustable channel for accommodation of the especially designed shade clamp 19. The shade clamp itself is of a practical type for holding the shade in place.

It is bodily pressed outwardly into frictional binding contact with the upper and lower walls of the channel 18 through the medium of the spring strip 24. Then too, the all metal arrangement of the device is an evident feature, as well as the spring pressed retaining latch 16 cooperating with the especially designed concavo-convex cap 12 on the right hand end of the roller construction.

It is thought that persons skilled in the art to which the invention relates will be able to obtain a clear understanding of the invention after considering the description in con-

nection with the drawings. Therefore, a more lengthy description is regarded as unnecessary.

Minor changes in shape, size, and rearrangement of details coming within the field of invention claimed may be resorted to in actual practice if desired.

I claim:

In a shade roller construction of the class described, a tubular roller provided with a longitudinal inwardly bent channel-shaped keeper the upper and lower walls of which are disposed in outwardly converging relationship, a shade, a clamping device for the upper end portion of said shade including a hooked retaining flange and a complementary securing lip, and a flexible retention strip interposed between the web portion of the keeper and the back of said clamping device, said retention strip serving to force said clamping device outwardly into binding and retaining relationship with the upper and lower walls of the keeper in the manner described.

In testimony whereof I affix my signature.
WILLIAM KAMPAS.
